United States Patent Office

Des. 201,552
Patented July 6, 1965

201,552

BRASSIERE

Charles M. Sachs, Fort Lee, N.J., assignor to Sarong, Inc.,
Dover, Del., a corporation of Delaware

Filed Sept. 3, 1963, Ser. No. 76,429

Term of patent 14 years

(Cl. D20—2)

The figure is a plan view of the front of a brassiere showing my new design, the back thereof being conventional.

I claim:

The ornamental design for a brassiere, as shown and described.

2,541,147 2/51 Becker,
2,753,563 7/56 Blitch.
